UNITED STATES PATENT OFFICE.

GERHARD ALMCRANTZ AND GIDEON TÖRNQVIST, OF CHICAGO, ILLINOIS.

ORCHESTRA-HARP.

SPECIFICATION forming part of Letters Patent No. 659,429, dated October 9, 1900.

Application filed April 4, 1900. Serial No. 11,471. (No model.)

To all whom it may concern:

Be it known that we, GERHARD ALMCRANTZ and GIDEON TÖRNQVIST, subjects of the King of Sweden and Norway, residing in the city 5 of Chicago, county of Cook, and State of Illinois, have invented certain new and useful Improvements in Orchestra-Harps, of which the following is a specification.

Our invention relates to stringed musical 10 instruments of the harp type, and has reference more particularly to that class or variety of harps commonly known as "auto-harps;" but by reason of the fact that our present improvements vastly extend the 15 scope and capacity of the common autoharp, enabling it with advantage to be employed in an orchestra where desired, we have given it the designation of "orchestra-harp."

The principal object of our invention is to 20 produce a musical instrument of the character named capable of rendering a larger number and variety of chords and arpeggios than can be obtained from the common instruments of this character through a convenient 25 arrangement of the keys or finger-buttons combined with a longitudinally-adjustable capacity of the damper-bars transversely of the strings of the instrument.

Other minor objects and purposes of the 30 invention will appear later in the subjoined description thereof.

Our invention is illustrated in the accompanying drawings, forming part of this application, in which—

35 Figure 1 is a plan view of a harp with our improvements applied thereto. Fig. 2 is a vertical transverse section, enlarged, through the damper-bars and their casing, in the line $x x$ of Fig. 1, looking in the direction of the arrow. Fig. 3 is a detail, broken away, in enlarged vertical section, of the lock mechanism, on line $y y$ of Fig. 1. Fig. 4 is another detail, broken away, in enlarged vertical section, showing the manner of adjustably 40 securing the damper-bar casing to the upper face or sounding-board of the harp, on the line $z z$ of Fig. 1. Fig. 5 is an enlarged detail, broken away, in plan view, showing the keys or finger-buttons which operate the 45 damper-bars and our preferred system of indicating the different chords which may

be obtained upon the manipulation of the several keys; and Figs. 6 and 7 are enlarged detail views, in vertical section, broken away, on the lines $z' z'$ and $z^2 z^2$, respectively, of 55 Fig. 1, showing an improvement in the nature of a hinged tailpiece for covering the anchor-pins of the strings.

Similar numerals of reference refer to similar parts throughout the several views. 60

1 designates the back, 2 the sides, and 3 the face or sounding-board, of our improved harp.

4 represents the strings, which, with the exception of the three or four lowest base- 65 strings, will be tuned according to the chromatic scale. The strings are secured in and wound about a series of pegs 5, which latter may be turned so as to bring the instrument into perfect tune by the usual tuning-pins 6, 70 connected to the pegs 5 by worm-gear, as common in guitars and similar instruments. By reason of the close proximity to each other of the pegs 5 the tuning-pins 6 will necessarily be arranged in two horizontal off- 75 set rows in the upper end of the body of the harp.

Mounted transversely of the harp and slidably supported at its two ends upon the face or sounding-board thereof, so as to span the 80 strings, is a casing or carriage 7, covering and inclosing a series of damper-bars 8. This casing 7 comprises a top board 9, two side pieces 10 10, and two end blocks 11 11. The inner opposing sides of the end blocks 11 11 85 are formed with a series of vertical grooves 12, in which the ends of the damper-bars 8 fit and are guided in their vertical movements, said damper-bars being normally held supported in their elevated positions out of 90 contact with the strings of the instrument by springs 13, as plainly shown in Fig. 3. On the under side of each damper-bar is glued or otherwise secured a series of felt pads or dampers 14 of varying lengths, so spaced 95 and disposed that when the bar is depressed they will stop or cut out all strings except such as will produce a certain musical chord. In the top of each damper-bar and at or near the longitudinal center thereof is secured a 100 pin 15, the tops of said pins being provided with keys or finger-buttons 16, preferably set

close together in parallel rows transversely of the damper-bar casing and in offset or staggered relation, as shown.

We have herein shown a series of twenty 5 damper-bars arranged side by side in close parallel order and having their felt dampers or stops so arranged that by depressing said bars by the keys 16 and sweeping the strings by the finger or a suitable pick we can produce 10 twenty different musical chords or arpeggios. The capacity of the instrument as thus described can be doubled by the simple mechanism which will now be described.

Each of the end blocks 11 has formed in 15 its base near each end a mortise 17, as shown in Fig. 4. These mortises when the damper-bar casing is in position are entered by four vertical posts 18, secured in the face or sounding-board of the harp and having eyes formed 20 through their upper ends, through which are removably secured, in the manner plainly shown in Fig. 4, horizontal pins 19. These pins 19 are arranged parallel with the long 25 side of the casing, and the posts 18 are of considerably less width than the mortises 17, whereby, it will be observed, the casing 7, carrying the entire series of damper-bars, is rendered capable of sliding a short distance, equal to the distance between two adjacent 30 strings, transversely of the body of the harp, such movement being limited in each direction by the contact of the inner faces of the mortises or recesses 17 with the opposite sides of the posts 18. In order to lock the casing 35 7 in the two extremes of its horizontal sliding movement, we prefer to employ the simple lock mechanism shown in Fig. 3. Here 19 indicates a small plate or strip of spring metal secured at 20 to the face of the harp 40 and extending over a shallow recess 21, formed in the latter. In this plate 19 are formed two apertures 22 and 23, which apertures are entered and engaged alternately by a small V-shaped pin or tooth 24 on the base of one 45 of the end blocks 11 when the casing 7 is at the two extremes of its sliding movement. A spring-supported push-pin 25, having a head 26 and passing vertically through the top board 9 and the end block 11, operates in an 50 obvious manner to disengage the tooth 24 and the spring-plate 19 when it is desired to shift the position of the casing 7 and its contained series of damper-bars.

In Figs. 1, 6, and 7 is illustrated a novel 55 and useful improvement we have devised in the nature of a hinged tailpiece to serve as a cover and shield for the series of anchor-pins to which the strings are secured. This consists of a recessed strip 27 of a length 60 corresponding to the width of the harp and of a width substantially equal to the depth of the body of the instrument. It is hinged at its lower edge, as at 28, to the under edge of the lower end of the body of the harp, and 65 is retained in its closed position, as shown, preferably by means of two thumb-nuts 29, 29, engaging a pair of threaded pins or bolts 30

30, passing through its opposite ends and screwing into one of the sides 2 of the body of the instrument. As an equivalent, a pair 7c of spring-hinges might be used, which would dispense with the necessity of the nuts 29 and bolts 30. The purpose of this tailpiece is to act as a guard and prevent the anchor-pins or the loose ends of the strings secured thereto from either causing or receiving accidental injury. When a broken or worn-out string has to be replaced by a new one, by simply removing the thumb-nuts 29, 29 the strip 27 can be swung down on its hinges, 80 thus exposing the anchor-pins and readily enabling such a string to be removed and a new one to be applied.

Referring next to Figs. 1 and 5, we will describe the method of notation we prefer to 85 employ to indicate the different chords or combinations of musical sounds which can be obtained by our improved harp, according to the tuning of the strings, the position of the damper-bar casing, and the depression 90 of the keys. Across the face of the sounding-board, near the lower end of the instrument, are two rows of musical characters arranged directly beneath the strings and indicating the notes to which the strings may 95 be tuned. On the top board or cover 9 of the damper-bar casing are two series of characters, one on each side of the bank of keys, each character in each series indicating a certain chord and being connected with one of the keys by an arrow, as shown. On the faces of the keys themselves are marked a third series of similar characters. When now 100 the strings are tuned, as indicated by the lower row of letters under the strings, and the damper-bar casing is secured in its upper or right-hand position, on applying any one of the damper-bars to the strings by depressing its appropriate key and sweeping the strings with the finger or pick that chord 105 will be produced which is indicated by the character on the right of the key, (or above it in Fig. 5.) When the damper-bar casing is shifted to and secured in its lower or left-hand position, the characters on the keys 110 themselves indicate the respective chords that will be obtained upon the depression of the several keys and the subsequent striking of the strings. When now the strings of the instrument are tuned half a tone lower, 115 as indicated by the upper row of letters under the strings, and the damper-bar casing is in its right-hand position, the chord yielded upon the manipulation of any key will still be that indicated on the face of the key itself, 120 while the other (left-hand) position of the damper-bar casing will bring the damper-bars into a position relatively to the strings to 125 yield the chords indicated by the respective characters on the left of the keys, (or below them in Fig. 5.)

It will thus be seen that by our improved harp, as above described, we are able to produce the major, minor, and seventh of every

chord of the chromatic scale, thus rendering the instrument universal in its application and capable of rendering music written in any key, whether the strings are tuned according to the upper or lower row of characters on the sounding-board.

The manner of playing our improved orchestra-harp will readily be understood from the foregoing description of its construction. The instrument can be tuned with the same facility as a guitar by means of the tuning-pins 6. Ordinarily the three or four lowest or base strings will be struck or picked by the thumb of the operator or by a suitable pick which may be worn on the thumb, while the rest of the strings not muted by the damper-bars are vibrated in quick succession by a sweeping or sliding movement of the pick across them, thus producing a rapid arpeggio. In the rendition of any musical composition the operator will tune the strings and adjust the position of the damper-bars so as to best enable him to render the chords and successions of harmonies or musical sounds called for by that particular piece.

Having thus described our invention, what we claim as new, and desire to secure by Letters Patent, is—

1. In a musical instrument of the character described, the combination with the body and strings of the harp of a casing spanning the strings transversely and carrying a series of vertically-movable spring-supported parallel damper-bars, means for slidably and removably securing said casing to the upper face of the harp, said means comprising a series of vertical posts formed on one of said parts and entering a corresponding series of mortises formed in the other of said parts, said posts having a limited play in said mortises, and a series of removable pins passing loosely through eyes in said posts and locking said casing to the harp-body, substantially as described.

2. In a musical instrument of the character described, the combination with the body and strings of the harp of a casing spanning the strings transversely and carrying a series of vertically-movable spring-supported parallel damper-bars, means for slidably and removably securing said casing to the upper face of the harp, said means comprising a series of vertical posts formed on one of said parts and entering a corresponding series of mortises formed in the other of said parts, said posts having a limited play in one direction in said mortises, and a series of removable pins passing loosely through eyes in the free ends of said posts and locking said casing to the harp-body, and means for automatically locking the casing in either extreme of its sliding movement, substantially as described.

3. In a musical instrument of the character described, the combination with the body and strings of the harp of a casing spanning

the strings transversely and carrying a series of vertically-movable spring-supported parallel damper-bars, means for slidably and removably securing said casing to the upper face of the harp, said means comprising a series of posts set in the upper face of the harp-body and entering a corresponding series of mortises formed in the end blocks of the casing, and having a limited play in one direction therein, and a series of pins removably secured through the end blocks of the casing and passing loosely through eyes in the upper ends of said posts and locking said casing to the harp-body, and means for automatically locking the casing in either extreme of its sliding movement, substantially as described.

4. In a musical instrument of the character described, the combination with the body and strings of the harp of a casing spanning the strings transversely and carrying a series of vertically-movable spring-supported parallel damper-bars, means for adjusting the position of said casing transversely of the strings, and means for locking the casing in either extreme of its movement, said means comprising a spring-metal plate or strip secured in the face of the harp and having a series of apertures, a pin or tooth on the base of the casing adapted to engage said apertures, and a spring-supported push-pin mounted in said casing above said plate or strip and adapted, when depressed, to disengage said plate from said tooth, substantially as described.

5. In a musical instrument of the character described, the combination with the body and strings of the harp of a casing carrying a series of damper-bars, said casing spanning the strings and being adjustable transversely thereof, and said damper-bars being arranged in close proximity and each provided with a vertical pin at or near its longitudinal center which extends up through a hole in the top board of the casing and terminates in a key, said keys being arranged in a plurality of parallel rows transversely of the casing, and each being marked with a musical character indicative of the chord which will be produced through the manipulation of said key when the casing is at one limit of its adjustment, and the top board of the casing bearing a series of musical characters connected with said keys and indicating the chords which will be produced by the manipulation of the keys when the casing is at the other limit of its adjustment, all substantially as shown and described.

In testimony that we claim the foregoing as our invention we have hereunto signed our names in the presence of two witnesses.

GERHARD ALMCRANTZ.
GIDEON TÖRNQVIST.
